PAPER CUTTING MEANS WITH A SUCTION
APPLYING DEVICE

Lawrence Littman, Ramsey, N. J., assignor, by
mesne assignments, to Advance Holding Corporation,
Upper Montclair, N. J., a corporation
of New Jersey

Application October 19, 1950, Serial No. 191,029

11 Claims. (Cl. 164—61)

1

The present invention relates generally to devices for cutting paper, and more particularly to such a device for cutting lengths of paper during movement through a portion of a printing press.

In printing operations it is frequently desirable to print matter on relatively large sheets or lengths of paper and to thereafter cut the printed lengths to smaller widths. While the paper could be first printed on one machine and then run through a separate cutting machine, this is objectionable due to the additional machinery, time and labor required. It is therefore preferred to cut the paper as it moves along some portion of a printing press. The latter presents difficulties however, as the printing and feed rollers of modern high speed presses require moving the paper at high speed, anything which might interfere with movement of the paper or cause it to tear, or would require slower press speed, is objectionable, as it would decrease the production rate.

Attempts have been made to produce a satisfactory device for cutting sheets during movement through a printing press, but they have presented various objections. Some have been too complicated or expensive, others have required making extensive changes to presses in order to install them, still others have tended to interfere objectionably with the sheets during their movement.

The present invention aims to overcome the above and other difficulties by providing a new and improved cutting device that may be readily installed in existing printing presses, as well as in new presses. The invention further contemplates the provision of a device which may be employed to cut rapidly moving lengths of paper without interfering with the moving paper or requiring slower speeds.

An object of the present invention is to provide a new and improved paper cutting device.

Another object of the invention is to provide an improved paper cutting device that may be readily and inexpensively incorporated in existing printing presses, as well as in new printing presses.

Another object of the invention is to provide an improved cutting device which does not hamper rapid movement of lengths of paper through printing presses.

Another object of the invention is to provide an improved cutting device which accurately severs moving lengths of paper.

A further object of the invention is to provide

2

an improved cutting device which embodies means for applying suction to only a narrow portion of a moving length of paper so as not to interfere with rapid movement of the material.

Still another object of the invention is to provide an improved cutting device which does not require a large supporting area for the material during cutting.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a fragmentary elevational view, partly in section, showing the present invention adjacent the discharge portion of a printing press;

Fig. 2 is a plan view illustrating a portion of the device shown in Fig. 1;

Fig. 3 is a fragmentary sectional view taken along the line 3—3 of Fig. 2; and

Fig. 4 is an elevational view, partly in section, showing a modified form of the invention.

Referring more particularly to Fig. 1, there is shown a portion of a rotatable printing press sprocket 3 over opposite ends of which travel chains (not shown) that carry gripping means 5 at spaced intervals across the width of the press. The gripping means 5 hold the leading or front edges of lengths of paper 6 and pull them toward a stack 7. The sprocket, chains and spaced grippers are indicated diagrammatically and are intended to represent those used in various commercially available printing presses.

In accordance with usual practice, lengths or sheets of paper, after being printed, are pulled generally vertically upwardly by the grippers and thence horizontally, being delivered from the latter horizontal position onto the upper surface of the stack 7. As the grippers travel horizontally, their high speed causes the sheet 6 to assume a horizontal position behind the grippers; that is, as the grippers travel horizontally, the sheets which they are pulling trail out behind them in horizontal position. The grippers are carried by their actuating chains about a closed path so that some sets of grippers are always moving lengths of paper away

from the printing rollers for delivery on the upper surface of the stack 7, and others are always moving toward the printing rollers for grasping additional sheets. For assisting in guiding the sheets during movement from generally vertical to horizontal positions there may be employed a curved guide plate 9.

Shortly after the grippers and sheets commence their horizontal travel, the sheets pass over a vacuum box 10 located immediately in front of a rotatable cutter 11. The vacuum box 10 is provided adjacent its rear wall with a narrow upwardly facing slot 13. A hose 16 may be connected with suction applying means such as a vacuum pump, so that air is withdrawn from the interior of the vacuum box and thus tends to create a suction or vacuum along the narrow upwardly facing slot 13. As paper is pulled over the vacuum box 10, suction is applied through the slot 13 along a narrow zone at the underside of the moving paper and holds the paper down along the length of the slot; applying suction only along the narrow slot provides minimum friction between the moving paper and the upper surface of the vacuum box 10, thereby avoiding objectionable retarding of the paper. As a result paper moves freely over the vacuum box and yet is pulled down along a narrow line immediately in front of the cutter 11. The vacuum box may be mounted on any suitable portion of the printing press structure.

The cutter 11 has its outer edge 12 close to the slot 13 of the vacuum box and the cutter rotates downwardly toward the slot (clockwise as shown in Fig. 1) so that it does not tend to lift the moving paper away from the vacuum slot 13. As the cutter rotates it severs the moving paper.

The cutter may be driven by a rotatable shaft 19 of a small air motor 20 connected with an air tube 23. The motor may be carried by an arm 21 and a set screw 22 may be employed to retain the motor 20 in position on the arm. While an electric motor may be used instead of an air motor, the latter is preferable as its small size minimizes the possibility of interference with adjacent parts of the printing press.

For facilitating vertical adjustment of the cutter 11 and also placing it close to the slot 13, the rear side 14 of the vacuum box is preferably inclined and the cutter mounting arm 21 is carried by a shaft 25 located below and adjacent the front of the vacuum box 10. When bolts 26, or other means employed to clamp the arm 21 on the shaft 25, are loosened the arm 21 may be turned about the shaft 25 to simultaneously change the elevation of the cutter and its spacing from the rear edge of the vacuum box; such adjustments may be necessary from time to time due to sharpening the cutters or due to setting up the device for cutting operations. The cutter may also be adjusted along the shaft 25 and clamped thereon to sever the paper at any desired location across its width.

In operation a continuous suction is supplied to the vacuum box through the hose 16, grippers pull lengths of paper over the suction slot 13 and suction is applied against the underside of the paper to hold it downwardly along a narrow line. The use of a partial vacuum in the box 10 and its application against the paper through the narrow slot 13, provides very accurate control of the force with which the paper is pulled down. The outer edge 12 of the cutter 11 is close to the slot and readily severs the moving paper. Since suction is applied to the moving paper only along

the slot 13, there is a minimum of retarding friction between the moving paper and the vacuum box. The cutter projects up into the air behind the box and it is not necessary to support the horizontally disposed moving paper at opposite sides of the cutter or behind it; in fact such additional supports would increase the frictional contact and tend to interfere with or impede movement of the paper.

In some instances it may be desired to provide vacuum plates at opposite sides of the vacuum box 10 to minimize any tendency for the moving paper to be pulled down into a sort of localized "valley" adjacent the vacuum box slot 13. As shown such a vacuum plate may comprise a board 26' of suitable shape mounted on top of auxiliary vacuum boxes 27. A number of small diameter spaced openings 29 through the auxiliary boxes 27 and upper board 26 permit application of suction to the underside of the paper at spaced points across its width and tend to hold outwardly disposed portions of the paper while suction is applied to the paper at the suction slot 13. Where such auxiliary vacuum plates are employed, the relatively small spaced openings 29 thereof apply a minimum retarding effect on the moving paper. When the vacuum plates are utilized at opposite sides of the vacuum box 10, they may be of any suitable length which does not interfere with travel of the grippers 5 or any other moving parts.

If paper is to be cut at more than a single location across its width the cutter and associated vacuum box may merely be duplicated at appropriate locations. If desired the vacuum plates shown may be used with each of the additional cutters and their vacuum boxes.

In Fig. 4 there is shown a modified form of the invention which differs from that of Figs. 1-3 in employing a vacuum box with upwardly projecting lip portions 30 forming a narrow slot through which suction is applied against the underside of the paper. In this form of the invention there is a minimum of contact between the paper and the vacuum box, as the moving paper comes into contact with only the uppermost edges of the slot-forming lips 30. As indicated in Fig. 4, it is not essential that a vacuum box and cutter be located immediately adjacent the discharge end of the guide plate 9, that shown in Fig. 4 being spaced any suitable distance from the guide plate 9a.

It will be seen that the present invention provides a new and improved device for cutting paper during movement thereof along a portion of a printing press. The cutter disc of the present machine projects up into the air where it may freely sever the horizontally moving paper and it is not necessary to support the paper alongside the cutter or behind it. Suction is applied against the underside of the moving paper along what may be referred to as a narrow "line" immediately in front of the cutter edge. There is a minimum of support at the underside of the paper and hence frictional contact between the paper and a support is reduced to an absolute minimum. The device of the present invention is preferably located at a portion of the machine through which the paper moves horizontally during operation of the press.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A device of the class described for cutting a length of paper during edgewise movement thereof comprising the combination of means for cutting the paper during said movement, means at one side of the path of movement of the paper for carrying and actuating said cutting means, and means at the same side of the path as said carrying and actuating means for applying suction to the paper at a location spaced in advance of said cutting means thereby to pull the paper toward said carrying and actuating means and the cutting means.

2. A device of the class described for cutting a length of paper during edgewise movement thereof comprising the combination of means for cutting the paper during said movement, and means having an outwardly exposed slot disposed generally transversely of the path of movement of the paper for applying suction to the paper along a zone transversely disposed to said cutting means and spaced in advance thereof to thereby facilitate engagement of the paper with said cutting means.

3. A device of the class described for cutting a length of paper during edgewise movement thereof comprising the combination of means for cutting the paper during said movement, means having an outwardly exposed slot disposed generally transversely of the path of movement of the paper and spaced in advance of said cutting means for applying suction to the paper along a zone transversely disposed to said cutting means to thereby facilitate engagement of the paper with said cutting means, and a projection extending about said slot forming a raised paper supporting lip.

4. A device of the class described for cutting a length of paper during edgewise movement thereof comprising the combination of means having an outwardly exposed slot disposed generally transversely of the path of movement of the paper for applying suction to the paper at a location in advance of a cutting means thereby to facilitate engagement of the paper with the cutting means, means having a cutting edge spaced rearwardly from said slot for cutting the paper during said movement, a shaft below said suction applying means and in advance of said slot, and an arm supporting said cutting means on said shaft for swinging movement of the cutting means about said shaft thereby to vary the height of said cutting edge and its spacing from said slot.

5. A device of the class described for cutting a length of paper during edgewise movement thereof in a horizontal plane, comprising the combination of means below said horizontal plane of movement having an upwardly facing exposed slot with longitudinal axis disposed generally transversely of the path of movement of the paper for applying suction to a lower surface of the paper through said exposed slot at a location in advance of a cutting means thereby to facilitate engagement of the paper with the cutting means, rotatable means projecting through said horizontal plane of movement having a cutting edge spaced from said slot for cutting the paper, and means for rotating said cutting means in a direction tending to urge the moving paper downwardly toward said slot.

6. A device of the class described for cutting a moving length of material comprising a rotatable disc cutter, means having an elongated narrow opening in advance of said cutter and

5. extending generally perpendicular to the plane of the cutter for applying suction to the moving material to pull it down during movement, and additional means at opposite sides of said first means having a plurality of spaced openings in general alignment with said elongated narrow opening for applying suction to the moving material at a plurality of spaced locations.

10. 7. A device of the class described for cutting longitudinally a length of paper or like sheet material comprising means for moving the sheet along a path in which a zone of the sheet intermediate its lateral edges passes successively over a supporting surface and thereafter through a portion of the path in which said zone of the sheet is unsupported, a suction box having a wall comprising said supporting surface and having therein a slot transverse to said path, a cutter having an edge in a plane normal to the plane of said slot, means positioning the cutter in the unsupported portion of the path with its edge intersecting the path, and means for applying suction to the box for maintaining said zone of the sheet engaged with the slotted wall of the box and guiding the sheet in its movement to the cutter.

20. 8. A device of the class described for cutting longitudinally a length of paper or like sheet material comprising means for moving the sheet along a path in which a zone of the sheet intermediate its lateral edges passes successively over a supporting surface and thereafter through a portion of the path in which said zone of the sheet is unsupported, a suction box having a wall comprising said supporting surface and having therein a slot transverse to said path, a cutter having an edge in a plane normal to the plane of said slot, means positioning the cutter in the unsupported portion of the path with its edge intersecting the path comprising a support extending toward the path from the side thereof on which the box is positioned, and means for applying suction to the box for maintaining said zone of the sheet engaged with the slotted wall of the box and guiding the sheet in its movement to the cutter.

30. 9. A device of the class described for cutting longitudinally a length of paper or like sheet material comprising means for moving the sheet along a path in which a zone of the sheet intermediate its lateral edges passes successively over a supporting surface and thereafter through a portion of the path in which said zone of the sheet is unsupported, a suction box having a wall comprising said supporting surface and having therein a slot transverse to said path, a rotary cutter having an edge in a plane normal to the plane of said slot, means positioning the cutter in the unsupported portion of the path with its edge intersecting the path, means rotating the cutter toward the box, and means for applying suction to the box for maintaining said zone of the sheet engaged with the slotted wall of the box and guiding the sheet in its movement to the cutter.

40. 10. A device of the class described for cutting longitudinally a length of paper or like sheet material comprising means for moving the sheet edgewise along a generally horizontal flat straight path, a suction box in the forward portion of said path having an upper surface provided with a slot transverse to said path and adapted to be engaged with the under surface of the sheet during said movement, and a cutter spaced behind said box having an edge in a plane normal

to said slot for severing said sheet, means supporting the cutter from below said path and positioning the cutter edge to intersect said path, and means for applying suction to the box.

11. A device of the class described for cutting longitudinally a length of paper or like sheet material comprising means for moving the sheet edgewise along a generally horizontal flat straight path, a suction box in the forward portion of said path having an upper surface provided with a slot transverse to said path and adapted to be engaged with the under surface of the sheet during said movement, a rotary cutter spaced behind said box having an edge in a plane normal to said slot for severing said sheet, means supporting the cutter from below said path and positioning the cutter edge to intersect said path,

means rotating the cutter toward the box, and means for applying suction to the box.
